UNITED STATES PATENT OFFICE.

GUSTAV JOHNSON, OF WEST ROXBURY, MASSACHUSETTS, ASSIGNOR, BY MESNE ASSIGNMENTS, TO CARR FASTENER COMPANY, A CORPORATION OF MASSACHUSETTS.

FASTENER.

Application filed January 7, 1927. Serial No. 159,687.

My invention aims to provide improvements in separable fasteners of the turn button type.

In the drawings, which illustrate a preferred embodiment of my invention:

Figure 1 is a perspective view of a box showing one use of the fastener;

Fig. 2 is an enlarged view of the assembled fastener showing a portion of the box 10 and showing the fastener in unlocked position;

Fig. 3 is a section on the line 3-3 of Fig. 2;

Fig. 4 is a section on the line 4-4 of Fig. 1, showing the fastener in locked position;

Fig. 5 is a side elevation of the button or head part before assembly with its carrying part; and

Fig. 6 is a rear elevation of the stud member as it appears when attached to its carrying medium.

Referring to the embodiment of my invention illustrated by the drawings, I have shown a turn button fastener particularly, though not exclusively, adapted for use as a closure fastener for cardboard boxes and the like.

The socket is formed from a single piece of metal and comprises a plate 1 having an elongated aperture 2 formed therein. The plate 1 is secured to the body portion 3 of the box (Fig. 1) by means of attaching prongs 4 located at the periphery of the plate 1, as shown by Figs. 3 and 4.

The stud member comprises a relatively thin flat plate portion 5 secured to the flap 3^a of the box by attaching prongs 6 in the same manner as the socket plate 1. A resilient button or head 7 is secured to the plate 5 by means of a pair of fingers 8-8 which are formed integral with the button or head and pass through an aperture 9 in the plate where they engage the straight sides of a rectangular wall 10 surrounding the aperture 9, as shown by Fig. 6. The free ends 11 of the fingers 8-8 are bent outwardly and downwardly against the plate portion 5. The width of the end portions of the fingers, which pass through the plate

5, are somewhat reduced to provide shoulders 12 at the edges of each finger for engagement with that face of the plate 5 opposite that face against which the free ends 11 are bent, as shown by Figs. 4 and 5. These shoulders 12 and the upset ends 11 hold the

button or head 7 and plate 5 in assembly, and also prevent axial movement of the button or head 7 relative to the plate 5.

The fingers 8-8 are free to yield with the button or head 7 so that, as the button or head is turned, the finger portions, which engage the wall 10, will contract and permit the head to be turned from locking to unlocking position, or vice-versa. When the button or head 7 is in locked or unlocked position, the flat sides of the fingers engage the straight sides of the wall 10, and thereby cooperate to effectively hold the button or head in a predetermined position so that it cannot be turned accidentally. Furthermore, the resiliency of the fingers 8-8 prevents rattle of the head 7 when the fastener is subjected to vibration.

When the stud member is secured to the flap 3^a, the plate 5 is located at the inner face thereof and secured in position by the prongs 6, as shown in Figs. 3 and 4. The button or head 7 extends from the plate 5 through an opening in the flap 3^a and extends beyond the outer face of the flap so that it may engage the socket in the manner hereinafter described.

The button or head 7 is preferably rectangular in outline and is adapted to pass through an aperture 13 in the body of the box and through the aperture 2 in the plate 1. These apertures are in alignment and both are rectangular in outline so that the head 7 may pass therethrough (Figs. 2 and 3) and then be turned so that the long diameter of the button or head lies across the short diameter of the aperture 2 in the plate 1, as shown in Fig. 4. A piece of relatively large gauge wire 14 may then be passed through the opening 15 in the button or head, and the ends brought together and sealed by a sealing part 16, as illustrated in Figs. 1 and 4.

While the button or head 7 may be turned when the sealed wire is in place, the combined dimensions of the wire and head 7 are more than the long diameter of the aperture 13 and therefore the fastener cannot be separated without breaking the seal 16.

I do not wish to be limited to the particular embodiment of my invention, as illustrated and described.

Claims:

1. A fastener installation comprising, in combination, a turn button stud member se-

cured to a carrying medium and a socket also secured to a carrying medium, said stud member comprising a flat plate secured against one side of the stud-carrying medium and a button or head carried by said plate, said button or head passing through and being located at the opposite side of the stud-carrying medium and having integral yieldable means secured directly to the plate 10 for turning movement relative thereto, said socket comprising a plate secured to the socket-carrying medium and an aperture through the plate and carrying medium through which said button or head may pass 15 to engage the socket and secure the two carrying mediums together and means cooperating between the plate of the stud member and yieldable means of the button or head to hold the button or head in predetermined 20 positions.

2. A turn button fastener, stud unit composed of two pieces only, one of said pieces comprising a relatively thin flat plate part having means whereby it may be attached 25 to a support, said plate part having a rectangular aperture therethrough, a button or head part comprising the other piece of the fastener stud unit, contractible and expansible fingers formed integral with and extending from said button or head part through said rectangular aperture in said plate part and engaged with said plate part to secure said parts together while permitting turning of one part relative to the other 30 and said contractible and expansible fingers being provided with shoulders engaging one 35

face of said plate to space said head part a substantial distance from said plate part and having their free ends bent against the other face of said plate to cooperate with said shoulders and prevent relative axial movement between said parts. 40

3. A turn button installation for cartons and the like comprising a socket member secured to one portion of the carton and presenting an oblong aperture therethrough, a stud member secured to another portion of the carton, an oblong button or head portion presented by said stud member, said button or head passing through both portions of said carton and through the aperture in said socket and adapted to be turned to secure said portions of the carton together and means for securing said fastener against separation even though said button 55 or head be turned to fastener separating position. 50

4. A turn button stud unit composed of two pieces only, one piece being in the form of a plate 5 having a rectangular aperture 60 9 and the other piece being in the form of a button or head part 7 having integral spacing fingers 8 provided with means 11 and 12 at one end which engage opposite faces of the plate 5 and secure the plate 5 65 and button or head part 7 together and said head part 7 being located at the other end of the fingers thereby being spaced a substantial distance from said plate 5. 60

In testimony whereof, I have signed my name to this specification.

GUSTAV JOHNSON.
